UNITED STATES PATENT OFFICE.

WILLIAM J. D. MILLER, OF HILLSBORO, MISSOURI.

REVERSING-GEAR.

No. 842,684.

Specification of Letters Patent.

Patented Jan. 29, 1907.

Application filed September 27, 1906. Serial No. 336,466.

To all whom it may concern:

Be it known that I, WILLIAM J. D. MILLER, a citizen of the United States, residing at Hillsboro, in the county of Jefferson and State of Missouri, have invented certain new and useful Improvements in Reversing-Gear; and I do hereby declare the following to be a full, clear, and exact description of the invention, such as will enable others skilled in the art to which it appertains to make and use the same.

This invention relates to reversing-gear for steam-engines; and it consists in the novel construction and combination of the parts hereinafter fully described and claimed.

In the drawings, Figure 1 is a longitudinal section through the reversing-gear. Fig. 2 is a plan view of the reversing-gear. Fig. 3 is an end view of the reversing-gear.

A is the driving-shaft of the engine, and B is a guide-block rigidly secured to the said shaft by a screw *b* or other approved fastening device.

C are two adjustable guide-plates secured to the guide-block. D are adjusting-strips between the said plates and the guide-block, and *d* are slots in the said plates. E are the screws which pass through the said slots and engage with the block.

F is an eccentric provided upon one side with a block having guide-grooves *f*. The block abuts against the guide-block B, and its grooves engage with the inturned edges *c* of the guide-plates C. The eccentric is provided with a hole or opening *g* to clear the shaft, and it has a slot *G* on one side of this hole.

H is an inclined operating-plate which is slidable in the slot *G* and provided with lugs *h*, which extend partly around the shaft and which form bearings which slide upon the said shaft.

I is a bar which projects from one end of the inclined operating-plate and which is slidable in a slot in the guide-block B.

J is a collar secured to the projecting end portion of the bar I and encircling the shaft A. The collar J is provided with a circumferential rib *j*, and K is a collar which engages with the said rib and which is provided with projecting pins *k* for the reversing-lever to engage with in the usual manner.

When the parts are in the positions shown in the drawings, the slide-valve of the engine is moved in one direction by means of the eccentric. When the collar J is slid longitudi-

nally upon the shaft by means of the reversing-lever, the inclined operating-plate moves the eccentric crosswise of the shaft A and places it in a position suitable for moving the slide-valve in the opposite direction, and the engine is consequently reversed.

The guide-block B has a cylindrical projection *b'* on it, which can be used as a pulley to drive the belt of a speed-governor.

What I claim is—

1. In a reversing-gear, the combination, with a shaft, and a guide-block secured thereto and provided with guide-plates; of an eccentric provided with a grooved block which is slidable on the said plates and against the end of the said guide-block, said eccentric having also an opening to clear the said shaft and a slot at one side of the said opening, and an inclined operating-plate slidable in the said slot and provided with a projecting bar for moving it back and forth, said plate having also guide-lugs which project from one side of it and which slide upon the said shaft.

2. In a reversing-gear, the combination, with a shaft, a guide-block secured to the said shaft, and guide-plates provided with in-turned end portions and adjustably connected to the said guide-block; of an eccentric provided with a grooved block which engages with the in-turned end portions of the said guide-plates and which abuts against the said guide-block, said eccentric having also an opening to clear the said shaft and a slot on one side of the said opening, and an inclined operating-plate slidable in the said slot and provided with a projecting bar for moving it back and forth, said plate having also guide-lugs which project from one side of it and which slide upon the said shaft.

3. In a reversing-gear, the combination, with a shaft, and a guide-block secured thereto; of an eccentric operatively connected with the said block and slidable crosswise of the said shaft, said eccentric having also an opening to clear the said shaft and a slot on one side of the said opening, and an inclined reversing-plate slidable in the said slot and having guide-lugs which project from one side of it into the said opening and which engage with and slide upon the said shaft.

In testimony whereof I have affixed my signature in the presence of two witnesses.

WILLIAM J. D. MILLER.
